FOLDING, PACKING, AND DISPLAY CONTAINER

Original Filed April 18, 1928

FIG. 2.

UNITED STATES PATENT OFFICE

ARNOLD J. TANNER, OF NORTH HAVEN, CONNECTICUT

FOLDING, PACKING AND DISPLAY CONTAINER

Original application filed April 18, 1928, Serial No. 270,924. Divided and this application filed February 4, 1929. Serial No. 337,305.

The present invention relates to containers useful for packing and displaying merchandise of various kinds and the invention resides more particularly in certain improvements in the structure and design of the container whereby, at the minimum cost of production, an efficient packing and display container is provided. This improved container is simple in construction, therefore, the operation of assembling and setting the same up for packing and display purposes is accomplished with facility. The improved container is furthermore so constructed and designed that the same may be employed for various kinds of merchandise which may be packed singly in the container or a number of articles may be packed therein and readily dispensed therefrom.

This application is a division of copending application Ser. No. 270,924, filed April 18, 1928.

Figure 1 is a perspective view showing the complete container in its assembled condition and as set up in position for displaying merchandise which may be contained therein;

Figure 2 is a perspective view showing the container in its closed condition;

Figure 3 is a plan view of a one piece blank of which the complete improved container is constructed.

Referring to said drawings the improved container is composed of a single blank comprising the body section 1 having attached thereto, and extending laterally from the extension 2. This extension is next scored to divide the same into the sections 3 and 4 of which sections 3 forms the end walls of the container when set up and the section 4 forms the front wall of the container. Said body section 1 is horizontally scored to sub-divide the same into a number of parallel sections of which the central section 5 forms the back wall of the container and depending section 6 forms the bottom of the container. The section 6 is extended and scored to provide double folding portions 7 and 8 and extending from portion 8 is the portion 9. The section 10 is extended upwardly from the central section 5 and provides the cover for the open top of the container. The section 11 extends from section

10 and said section 11 serves to cover the front of the container and also provides a display surface when the cover is opened to show the merchandise therein.

Flap 12 extends from section 11 and this flap is arranged to fold and has the tongue 13, which together with the flap serves to hold the cover in its closed position and also to retain the display device in its raised position.

The blank shown in Figure 3 is required to be printed on one side only because throughout when in the erect position as a container, only one side of the blank is prominently exposed.

In setting up the blank already partly assembled by the machine operation in which the free end 14 of the lateral extension is adhesively secured to the glue lap 15, the first hand operation is to fold the flaps 16 which extend from the sections 3. The section 6 is then folded and the double folding portions 7-8 are folded over the front wall section 2, which latter is preferably cut out at 16 to provide an opening in the front and also a recess for the double folding portions 7 and 8, which when folded lie respectively over the front and back surfaces of the front wall. The section 9 is then folded to rest on the bottom of the container and the free end of the section 9 abuts against the back wall 5 of the container. Folding flaps 18 are provided at the top of section 4 and these flaps 18 serve to effectually close the ends of the container and also operate as stops to hold the cover in its raised position, when the latter operates as a display device. When closing the container the cover sections 10 and 11 are folded over the open top and front of the container, and the flap 12 is held in the closed position by means of tongue 13, and the slot 19.

It will be gathered from the above description of the invention that the improved container is simple in form and economical to manufacture. The simplicity is found to be of great advantage in the assembling and packing of the merchandise and the dealer desiring to utilize the container as a display medium for the goods contained therein can

readily set the container up for display without necessity of reading directions and illustrations to show the proper method. In fact, the dealer cannot do otherwise than set up the box correctly.

Various modifications may be made in carrying out the details of the invention hereinbefore described and it is to be understood that any modification coming fairly within the terms of the appended claims shall be covered thereby.

I claim:

1. A container and cover therefor composed of a single blank comprising a body portion with a lateral extension therefrom, said body portion forming the cover, back wall and bottom of the container, said extension being united to said body to form the front and end walls of the container, a depending portion of said body portion connected to said back wall providing the bottom of the container, the free end of said depending portion being arranged to fold over said front wall whereby said bottom is held in a suspended position, and an upwardly extending portion of said body in substantial alignment with said depending portion being arranged to form said cover.

2. A container and cover therefor composed of a single blank comprising a body portion with a lateral extension therefrom, said body portion forming the cover, back wall and bottom of the container, said extension being united to said body to form the front and end walls of the container, a depending portion of said body portion connected to said back wall providing the bottom of the container, the free end of said depending portion being arranged to fold over said front wall whereby said bottom is held in a suspended position, an upwardly extending portion of said body in substantial alignment with said depending portion being arranged to form said cover, and said upwardly extending or cover portion being arranged to fold over the top and front wall of the container and to be secured in the closed position by means located at the bottom of the container.

3. A container and cover therefor composed of a single blank comprising a body portion with a lateral extension therefrom, said body portion forming the cover, back wall and bottom of the container, said extension being united to said body to form the front and end walls of the container, a depending portion of said body portion connected to said back wall providing the bottom of the container, the free end of said depending portion being arranged to fold over said front wall whereby said bottom is held in a suspended position, an upwardly extending portion of said body in substantial alignment with said depending portion being arranged to form said cover, said up-

wardly extending or cover portion being arranged to fold over the top and front wall of the container and to be secured in the closed position by means located at the bottom of the container, said cover portion being arranged to fold on itself to form a display device and means for retaining the said display device in the display position.

4. A container of the class described composed of a single blank, said blank having a body portion arranged to form the bottom, back wall and cover of the container, a lateral extension from said body portion in alignment with the part of said body portion forming the back wall, said extension being arranged to be folded and united to said body to form the front and side walls of the container, a part of said body portion extending above said lateral extension being arranged to form the cover for the container and a part of said body portion depending below said lateral extension forming the bottom of the container.

5. A container and cover therefor formed of a single blank having a body portion and an extension at one side only thereof, said extension being secured at the free end of the other side of said body portion, said extension forming the front and side walls of the container, a part of the said body portion depending below said extension forming the bottom of said container, means for suspending the free end of said bottom from said front wall, another part of said body portion extending above said extension forming said cover arranged to fold over the top, front wall and bottom of the container and means for retaining said cover in the closing position.

Signed at New Haven, county of New Haven, State of Connecticut, this first day of February, 1929.

ARNOLD J. TANNER.
